(57) **CLAIM**

The ornamental design for a vehicle hood, as shown and described.

DESCRIPTION

FIG. 1 is a front left perspective view of a vehicle hood according to the present invention.

FIG. 2 is a rear left perspective view of the vehicle hood shown in FIG. 1.

FIG. 3 is a front right bottom perspective view thereof.

FIG. 4 is a rear right bottom perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a top view of the vehicle hood shown in FIGS. 1-10, mounted on a vehicle, with the rest of the vehicle shown in de-emphasized and half-tone portions so as to illustrate environmental structure. These portions form no part of the claimed design. More particularly, in FIG. 11, the inventive vehicle hood is shown within the broken line, and the elements shown outside of the broken line form no part of the claimed design, but are instead included to show environmental aspects thereof.
